UNITED STATES PATENT OFFICE.

ELLIOTT M. STORY, OF BRAINTREE, MASSACHUSETTS.

TOY.

1,379,944.

Specification of Letters Patent. Patented May 31, 1921.

Application filed August 2, 1920. Serial No. 400,587.

To all whom it may concern:

Be it known that I, ELLIOTT M. STORY, a citizen of the United States, residing at Braintree, in the county of Norfolk and 5 State of Massachusetts, have invented new and useful Improvements in Toys, of which the following is a specification.

This invention relates to a toy of the catapult type, adapted to be held by one hand 10 and provided with an arrow guide and an elastic strip adapted to be stretched by the other hand and released to project an arrow inserted in the guide.

The invention has for its object to provide 15 a toy of this character, of simple and relatively inexpensive construction, adapted to be used effectively by children.

The invention consists in the improvements which I will now proceed to describe 20 and claim.

Of the accompanying drawings forming a part of this specification,—

Figure 1 is a perspective view of the head portion of a toy embodying the invention.

25 Fig. 2 is a perspective view of the arrow portion.

Fig. 3 shows the head portion in section, and a side view of a portion of the arrow engaged with the elastic strip.

30 The same reference characters indicate the same parts in all of the figures.

The hand piece of my improved toy includes a head 12, having a horizontally extended arrow-guide 13, and a handle 14 35 fixed to the head, the handle being substantially perpendicular to the guide 13.

To the head 12 are fixed, preferably by staples 15, the ends of an elastic looped strip 16, preferably of elastic rubber, similar to 40 that used in making ordinary rubber bands, the fixed ends of the strip being adjacent to one end portion of the guide 13.

The head has relatively wide vertical side faces 17, and relatively narrow vertical end 45 faces 18, so that the head is of generally oblong form, the guide 13 being the wall of a horizontal circular hole bored in the head, from one end face 18 to the other, between the side faces 17.

0 The toy also comprises an arrow, including a head 19, and a slender shaft 20,

The diameter of the guide 13 is considerably greater than that of the shaft 20, so that the arrow may have a lateral movement of considerable amplitude in the guide. The 55 lower portion of the guide forms a rest, adapted to support and guide the arrow horizontally, as indicated by full lines in Fig. 3, which represents the arrow retracted and held in position to elongate the strip 16, 60 so that upon the release of the strip and arrow, the latter is projected from the guide by the contraction of the strip.

The rest formed by the lower portion of the guide is adapted to support a considerable portion of the length of the arrow, and initially guide the latter in a horizontal path, or a path which is substantially at right angles with the major axis of the handle. The lateral movability of the arrow 70 in the guide enables the user to variously incline the arrow, as indicated by dotted lines in Fig. 3, so that the initial path of flight of the arrow may be variously inclined relatively to the major axis of the 75 handle.

I claim:

A toy comprising a hand piece including a head having a horizontally extended arrow-guide and a handle fixed to the head 80 and substantially perpendicular to the said guide, and an elastic looped strip fixed at its ends to the head adjacent to one end portion of said guide, and an arrow including a shaft formed to have a lateral movement of 85 considerable amplitude in the guide, and adapted to be projected from the latter by the contraction of said strip, the lower portion of the guide forming a rest adapted to support and guide the arrow horizontally 90 and the lateral movability of the arrow in the guide permitting various inclinations of the arrow relatively to said rest, the said head being a block having relatively wide vertical side faces, and relatively narrow 95 vertical end faces, and the said guide being the wall of a horizontal circular hole bored in the block from one end face to the other, between the side faces.

In testimony whereof I have affixed my 100 signature.

ELLIOTT M. STORY,
